(57) **CLAIM**

The ornamental design for a microscope, as shown and described.

DESCRIPTION

FIG. 1 is a perspective view of a microscope showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Broken lines in the drawings are boundary lines that form no part of the claimed design. The light gray deemphasized area within the boundary lines shows a portion of the article that forms no part of the claimed design.

1 Claim, 7 Drawing Sheets
